(57) CLAIM

The ornamental design for a chaise, as shown and described.

DESCRIPTION

FIG. 1 is a front perspective view of the chaise showing my design.

FIG. 2 is another front view thereof;

FIG. 3 is a top view thereof;

FIG. 4 is a side view thereof;

FIG. 5 is an opposite side view thereof; and,

FIG. 6 is a back view thereof.

The broken lines shown on the chaise are understood to represent stitching.
